UNITED STATES PATENT OFFICE.

WILLIAM S. LAYCOCK, OF SHEFFIELD, COUNTY OF YORK, ENGLAND.

SPRING-ROLLER.

SPECIFICATION forming part of Letters Patent No. 271,339, dated January 30, 1883.

Application filed September 19, 1882. (No model.) Patented in England July 14, 1882, No. 3,344.

To all whom it may concern:

Be it known that I, WILLIAM SAMUEL LAYCOCK, of Sheffield, in the county of York, Kingdom of Great Britain, have invented certain new and useful Improvements in the Construction of Self-Acting Window-Blind Apparatus; and I do hereby declare that the following is a full, clear, and exact description thereof, reference being had to the accompanying drawings, which form a part of this specification.

My invention relates to improvements in the construction of self-acting window-blind apparatus or "curtain-fixtures" of that class which allow a weighted rolling blind or window-curtain to be drawn down to any desired position and support it in such position till the weight of the blind is relieved by the hand of the operator, when a spring or weight automatically winds it up, such apparatus being especially applicable to the rolling window-blinds of railway-cars.

The object of my invention is to obtain certainty of action, together with simplicity of construction, in apparatus or fixtures of the aforesaid class; and I attain this result by the combinations of mechanism illustrated on the annexed sheet of drawings, in which—

Figure 1 is an elevation of a blind-roller furnished with the preferred species of my said apparatus, Figs. 2 and 3 being views of the latter in directions opposite to each other and at right angles to that of Fig. 1; and Figs. 4, 5, and 6 are like views of another roller and apparatus, illustrating a modification of my invention, shown partly in section.

Similar letters refer to similar parts throughout the several figures.

Figs. 1, 2, and 3 represent, as aforesaid, my preferred arrangement of parts, the mechanism being located outside the roller. A is the roller, to which the weighted blind is attached, the roller-axes being supported by plates B B, in which they are free to rotate. At one end the axle has a pinion, C, fast thereon, and gearing therewith is a spur-wheel, D, which is actuated by a coiled winding-spring, E, one end of the spring being attached to the wheel and the other to a stud, F, on the adjacent plate. This arrangement of a wheel and pinion is for the purpose of obtaining the required number

of revolutions of the roller with the least variation in the power of the spring. G is a plate to retain the coils of the spring in position. At the other end of the roller a "friction-plate," H, is secured on the axle. A ratchet-wheel, I, is mounted loosely on this axle, being free to revolve in the direction of the winding-up action. A catch-pawl, J, prevents it revolving in the contrary direction. The ratchet-wheel is pressed against the friction-plate by a spiral spring, K, surrounding the shaft, the pressure being readily adjustable by means of a nut and lock-nut, L, applied to the screw-threaded end of the shaft. The blind is drawn down by the application of sufficient power to overcome the resistance of the frictional contact of the ratchet-wheel and cause the frictional surfaces, which may be plain or waved, to slip; and by relieving the roller in part of the weight of the blind by lifting the latter the spring is enabled to wind it up.

In the modification of my invention, illustrated by Figs. 4, 5, and 6, the winding-spring P is of a more common form, being an internal and direct-acting spiral spring. The axle M is held against rotation in the bracket N at one end of the roller, and is supported at its other end in a bearing, O, within the roller. The spring P is secured at the end Q to the fixed axle M, and at the other end, R, to the bearing O. The action of drawing down the blind carries round the end R of the spring, coiling it up sufficiently to draw up the blind when required. S is a short piece of tube driven tightly into the other end of the roller, and carrying a short axle, M², provided with a ratchet-wheel, I, friction-plate H, spiral spring K, and adjusting-nuts L, substantially identical with those before described, save that these are arranged within the roller, a simple bracket, N², forming a bearing for the said axle M², coacting therewith to support its end of the roller, and provided with a pawl, J, to coact with said ratchet-wheel I.

I am aware that prior to my invention window-blind apparatus or curtain-fixtures have been made with springs that are wound up by the operation of drawing down the blind, and with friction devices to aid in supporting the blind in any desired position, and I therefore

do not claim such arrangements, broadly; but
What I do claim as my invention, and desire
to secure by Letters Patent, is—

1. In "window-blind apparatus" or curtain-
fixtures operating as herein specified, the com-
bination, with a rotary axle and a fixed sup-
port therefor, of a friction-plate, H, ratchet-
wheel I, pawl J, spiral spring K, and adjust-
ing-nuts L, substantially as shown and de-
scribed, for the purpose set forth.

2. In window-blind apparatus or curtain-
fixtures operating as herein specified, the com-
bination, with a roller, A, having an "axle" at
each end rotating therewith, and plates B B,

forming bearings for said axles, of the pin-
ion C, spur-wheel D, winding-spring E, fric-
tion-plate H, ratchet-wheel I, pawl J, spi-
ral spring K, and adjusting-nuts L, arranged
outside the roller A and behind said plates B,
as shown in Figs. 1, 2, and 3, for the purpose 20
set forth.

In testimony that I claim the foregoing as
my own I have affixed hereto my signature in
presence of two witnesses.

W. S. LAYCOCK.
